COMBINED VEHICLE GRILLE AND HEAD LAMP GUARD

Frank J. Faulhaber, New York, N. Y.

Application May 7, 1956, Serial No. 41,374

Term of patent 14 years

(Cl. D14—6)

I claim:

The ornamental design for a combined vehicle grille and head lamp guard, substantially as shown.
